UNITED STATES PATENT OFFICE

SAMUEL C. SHAFFNER, OF CHICAGO, ILLINOIS

WASHING MACHINE

Application filed December 23, 1929. Serial No. 415,944.

My invention relates to an improved construction of washing machine by which the liquid and other materials employed may be thoroughly intermingled, and by which clothing, dishes and other articles may be thoroughly washed or cleaned, as desired. By my invention, I provide a casing for containing the liquid employed, which casing also forms a part of the housing of the motor employed, thus materially reducing the cost and weight of the machine from what it would be if the motor had its own independent housing. The motor employed is preferably of the electric type, having an impeller of one kind or another, mounted directly upon its shaft, thus eliminating all gearing and belting from the machine, the impeller being so housed in the casing that the liquid in the casing has imparted to it a vigorous circulation which is effective in mixing the liquid and other materials employed, and is also effective in bringing the liquid into engagement with all parts of the articles being washed or cleaned. The casing of the machine is provided with ample and unrestricted passageways for the flow of the liquid directly to the impeller, the path of flow of the liquid being restricted adjacent the impeller to effectively produce fluid flow by the impeller and a passageway is provided from the impeller, to deliver the liquid into the casing of the machine in a thin sheet across the entire bottom wall of the casing, and at high velocity against a curved wall of the casing, to thoroughly agitate the articles being washed or cleaned if they are fabrics of one kind or another, or to effectively reach all surfaces of the articles being washed or cleaned, if they are dishes or similar inflexible and rigid articles. In my construction, I further provide cap members for engagement with the casing, to complete the motor housing and prevent liquid entering said housing, and to complete the liquid passage-way adjacent the impeller, so that by removing these cap members, the motor stampings, the motor shaft and the impeller may be installed or removed as desired, as a unit.

My machine may be used either with or without a rotary cylinder, as desired, when

washing or cleaning fabrics and similar articles, and when the machine is used to wash or clean dishes or other articles of rigid nature, a supporting basket may be placed in the machine to hold the articles in position to be engaged by the circulating liquid. By my machine, I thus provide a construction by which articles of any nature may be washed or cleaned, without change in the construction of the machine, the basket for holding rigid articles and the cylinder for holding fabrics being readily insertable and removable to permit the use of the machine in any manner desired. In some cases it may be desired to use the machine principally as a dish washing machine or as a machine for washing other articles of rigid nature, and to facilitate this I provide a pipe of relatively small cross section which may be interchangeably mounted in the machine with the gate used to determine the velocity of flow of the liquid from the impeller, to the end that the liquid may be projected forcibly from discharge apertures over the articles being washed or cleaned.

My invention will best be understood by reference to the accompanying drawings showing a preferred embodiment thereof, in which

Fig. 1 is a vertical, central, sectional view through my machine, taken through the shaft of the motor and transversely of the axis of the cylinder, this view being taken along the line 1-1 in Fig. 2.

Fig. 2 is a partial side elevation of the machine shown in Fig. 1.

Fig. 3 is a vertical sectional view of the casing of the machine shown in Fig. 1, taken along the line 3-3,

Fig. 4 shows in perspective view a basket that may be used in connection with the machine,

Fig. 5 shows in front elevation to an enlarged scale a protective grid which is preferably employed in the machine,

Fig. 6 shows in a view similar to Fig. 1 a part of the casing of the machine and a modified type of impeller,

Fig. 7 is a sectional view of the parts shown in Fig. 6 taken along the line 7-7,

Fig. 8 is a vertical sectional view through a liquid discharge pipe and nozzle construction that may be used with the machine, and

Fig. 9 is a bottom view to an enlarged scale 5 of the nozzle construction shown in Fig. 8 taken along the line 9—9.

Similar numerals refer to similar parts throughout the several views.

As shown in Figs. 1, 2 and 3, the machine 10 consists of a casing 10 which preferably is of cast metal, for example a die casting, which may be conveniently made in two symmetrical parts joined in any convenient manner, for example by acetylene welding along the 15 plane indicated by line 1—1 in Fig. 2. The side wall 11 of the casing is provided with a semi-cylindrical recess 12 constituting half of the housing of the motor employed to operate the machine, which motor, as indicated in Fig. 1, is provided with an armature or rotor 13 mounted on a vertical shaft 14, field magnets 15 and field windings 16, it being understood that any desired type of motor may be employed. The side wall 11 20 of the casing is provided with small recesses co-axial with the shaft 14 to support the bearings 17 and 18 of the motor. A flanged cap member 19, semi-cylindrical in form and having recesses in it similar to the recess 25 30 12 and the bearing recesses in the side wall 11, is secured to the side wall 11 in any convenient manner, for example by screws 20, to complete the motor housing and the supports for the bearings 17 and 18. In this 35 manner, the parts of the motor are held in proper relative position by the side wall 11 and the cap member 19 and an independent housing for the motor is not required. The shaft 14 tends, as will be described, to move 40 upwardly, and to take the upward thrust a hardened steel ball 21 is preferably placed between the upper end of the shaft and the end of the recess for the bearing 17, said ball being surrounded preferably by fibrous material 22 which serves the double purpose of 45 holding the ball 21 centrally in its recess, and holding oil to lubricate the ball and shaft, which oil may be supplied to the material 22 through an oil hole 23.

50 Below the recess 12, the side wall 11 is provided with a second recess 24 to receive a stuffing box 25 around the shaft 14, where said shaft enters the impeller compartment 26 of the machine. The shaft 14 has rigidly 55 secured thereto in said impeller compartment, an impeller 27 which, for the construction shown in Fig. 1 is preferably of the type producing a thrust axially of the shaft and downwardly on the liquid, when the shaft is 60 rotated. The impeller compartment 26 consists in part of a semi-cylinder passageway 28 formed in the casing 10 and in part of a similar passageway in a flanged cap member 29, secured to the side wall 11 in any suitable 65 manner, for example by screws 30 as indi-

cated in Fig. 2. The passageway 28 is of sufficient extent vertically to contain the impeller 27, and above the impeller, the wall of the passageway continues horizontally outwardly to the end walls of the casing 10 70 in the form of partitions 31 and 32, which preferably incline upwardly slightly to direct liquid in the casing downwardly to the impeller compartment. The upper end of the impeller compartment is sufficiently below the lower end of the recess 24, so that the liquid in the casing 10 may flow freely 75 below the recess 24 into the impeller compartment. The lower end of the impeller compartment is continued by oblique walls 33 and 34 extending to the end walls of the casing adjacent its bottom wall, to direct the liquid delivered from the impeller 27, downwardly and laterally across the bottom wall 80 of the machine. The inner edges of the partitions 31, 32, 33 and 34 are preferably connected by an integral vertical wall 35 forming a continuation of the inner wall of the impeller compartment 26, and to this wall 35, a gate 36 extending across the lower portion 85 of the machine from end to end, is secured in any convenient manner, for example by screws 37, the lower edge of the gate being at such a distance from the bottom wall of 90 the machine, that the liquid delivered from the impeller is discharged in a thin sheet extending from end to end of the machine and at high velocity in the direction of the arrow 38.

The cap member 29 at its upper edge, 100 co-operates with the adjacent edge of the side wall 11 to support a threaded sleeve 39 forming a bearing for the shaft 14 above the impeller 27, which sleeve is held in place by a nut 40, suitable packing material being preferably disposed under the nut 40 and the flanged head of the threaded sleeve 39, to make a tight joint between the sleeve and the adjacent portions of the cap member 29 and side wall 11. The upper end of the sleeve 39 105 has threaded thereon, the stuffing box 25, by which leakage around the shaft 14 through the sleeve 39 is prevented.

The liquid delivered from the impeller 27 in the direction indicated by the arrow 38, 110 engages the cylindrically shaped side wall 42 of the casing, the curvature of which is carried part way across the bottom wall of the casing, so that the liquid will engage this cylindrically shaped surface tangentially 115 and be deflected by it upwardly to impart a whirling motion to the liquid in the casing 10. The upper edges of the side walls 11 and 42 are provided with ears 43 and 44 through which rods 45 and 46 extend to support handles 47 and 48, which handles are preferably of non-conducting material, for example wood to facilitate moving the machine from one location to another. The rod 46 also forms the pivotal support for ears 49 ex- 120 125 130

tending from a cover 50, having a downwardly extending flange 51 fitting the upper edge of the casing to close the machine. The edge of the cover 50 adjacent the handle 47, is 5 preferably provided with a spring clip 52 engaging the handle 47 for the closed position of the cover so that it is retained in its closed position, the clip 52 also providing a means for readily opening the cover when 10 desired. The cover 50 is preferably provided adjacent the side wall 42 with a curved deflector 53 extending from end to end of the machine to receive the whirling liquid from the upper portion of the side wall 42 and direct it downwardly into the central portion of the casing, said deflector being secured preferably to the flange 51 of the cover in any convenient manner, for example by screws 54 as indicated.

20 Within the casing 10, a cylinder 55 is mounted for rotation in bearings 56 carried by the end walls of the casing, which cylinder consists of end walls 57 held parallel with and adjacent the end walls of the casing, by 25 cross ribs 58, between which perforated screens 59 extend to retain the contents of the cylinder during a washing operation. The end walls 57 of the cylinder are preferably mounted co-axially with and adjacent to the 30 cylindrical surface of the side wall 42 as a result of which the liquid delivered against the side wall 42 strikes the ribs 58 and rotates the cylinder in the direction of the arrow 60. The screens 59 are of sufficiently 35 large mesh so that the liquid may freely enter and leave the cylinder and they are of sufficiently small mesh so as to retain small articles in the cylinder. The ribs 58 preferably project outwardly beyond the screens 59 a 40 sufficient distance to serve as driving vanes and they also project inwardly from said screens sufficiently to produce a tumbling effect on the articles contained in the cylinder and being washed or cleaned. It will be 45 understood that these ribs may project either outwardly beyond the screens or inwardly therefrom to any extent desired, depending upon the purpose for which the machine is intended in any case, and that if desired they 50 may be proportioned so that they do not project into the cylinder beyond said screens. The cylinder is provided with a door consisting of end bars 61 pivotally mounted on a rod 62 supported by the end walls 57 of the 55 cylinder, between which bars, ribs 58a similar to the ribs 58, extend, and between which ribs 58a and the rod 62, screens 59a similar to the screens 59 are disposed. The ends of the bars 61 remote from the rod 62, are 60 preferably extended inwardly as indicated at 61a, to receive spring actuated catches 63 carried by the end walls 57 of the cylinder, to hold the door in closed position.

To prevent bits of fabric and lint from 65 collecting on the impeller 27, I find it de-

sirable to place a screen 64 of relatively fine mesh across the path of the liquid flow as it approaches the impeller, this screen being preferably secured to the side wall 11 and to the wall 35 and extending from end to end of the machine.

The bottom wall of the casing adjacent the arrow 38 is preferably inclined upwardly above the tangential plane of the surface of the wall 42, sufficiently to direct the flow of liquid against the ribs 58 and 58a, to insure positive engagement between the liquid and the ribs. The casing 10 is provided with feet 65 and 66 which are preferably integral with the casing and provided at their lower ends with pads 67 of resilient material, for example rubber. The foot 65 may conveniently be located in the plane indicated by the line 1-1 in Fig. 2 so that it is formed in part on each of the portions of the casing during the casting of the same, which facilitates the insertion of the pad 67 in the foot in assembling the machine. The feet 66 are preferably located adjacent the ends of the cap member 29 and so disposed that half of each of these feet, consists of an extension from the casing, and the other half consists of an extension from the cap member, so that the pads 67 may be conveniently located in the feet when the cap member 29 is applied to the casing. The cap member 29 is preferably provided with an extension 68 having an aperture in its lower wall to receive a plug 69 carried by the lower end of a rod 70 extending through a stuffing box in the upper wall of the extension 68, the upper end of the rod 70 having secured thereto a handle 71 by which the rod may be raised and lowered as desired. The plug 69 constitutes an outlet valve for the machine, to drain the liquid from the casing when desired. With the exception of the extension 68 and the parts carried thereby, the machine is preferably symmetrical about the plane indicated by the line 1-1 in Fig. 2.

From the construction described, it will be understood that desired articles may be washed or cleaned by placing them in the cylinder 55 and placing in the casing, the liquid or materials to be used to effect the washing or cleaning, which liquid or materials may have a depth such that sufficient clear space will be left above it to permit the free circulation of the liquid through the casing and through the impeller. The vigorous circulation of the liquid resulting from the action of the impeller, and the tumbling of the articles in the cylinder, bring all parts of the articles into contact with the rapidly moving liquid and effective washing or cleaning of the articles is secured. In some cases, it is desirable to use the machine without the cylinder 55, in which case the cylinder may be readily lifted from its bearings 56 and removed from the casing and the

washing or cleaning operation may proceed by placing the articles to be washed or cleaned in the casing itself, in which event the rapidly moving liquid, due to its circular motion against the end wall 42 and against the deflector 53, agitates the fabric or other articles being washed or cleaned, to bring all portions of the fabric or articles into contact with the liquid and thus effect the cleaning 10 operation.

In cases where the cylinder 55 is not used, I find it desirable to prevent the articles, particularly if they be fabrics, from directly engaging the screen 64, since their engagement 15 with the screen 64 would tend to prevent the free flow of the liquid to the impeller 27. To secure this result, I preferably provide a grid 72 across the path of the liquid flow adjacent the screen 64, which grid as more 20 clearly shown in Fig. 5, consists of a plurality of bars or rods 72a extending vertically between upper and lower cross bars 73 and 74, the grid being of a sufficient width to extend from end to end of the machine. 25 The grid 72 may be conveniently supported in the machine by hooks 75 extending inwardly from the upper portion of the side wall 11, the thickness of the flange 51 being preferably sufficient to cover the bar 73 and 30 the hooks 75, to prevent the possibility of fabrics being washed or cleaned, catching on the hooks 75. This construction permits the ready removal of the grid 72 from the hooks 75 and from the machine when it is not desired 35 to use the grid, for example when the cylinder 55 is employed to contain the articles being washed or cleaned.

It will be understood that any materials whatever that are adapted to wash or clean 40 articles, where the resulting washing or cleaning medium is in liquid form, may be employed in my machine, and that any articles which can conveniently be located in the machine and which are susceptible of 45 such washing or cleaning, can be washed or cleaned by the operation of my machine. I find that the vigorous circulation produced by the impeller and the agitation of the liquid resulting from its passage through the 50 machine, effectively mixes the materials of the cleaning medium and that in fact my machine may be used effectively as a mixing machine where it is desired to thoroughly mix materials at least one of which is a liquid. 55 My machine is also particularly effective in connection with all kinds of washing operations where water and soap or equivalent materials are employed and for all forms of dry cleaning operations where liquids which 60 are good solvents of grease and dirt are employed, for example gasoline.

While in Fig. 1 I show an impeller 27 of the type producing a thrust on the circulating liquid, axially of the shaft 14, it 65 will be understood that any other type of

impeller may be employed that will vigorously circulate the liquid, for example, in Figs. 6 and 7 I illustrate a modified form of impeller of the centrifugal type, by which the liquid is forced outwardly in radial directions from the impeller. In this construction, the shaft 14a extends through a stuffing box 25a and bearing 39a and has secured to its lower end an impeller 27a having radially disposed curved blades 27b. 70 The impeller 27a is mounted in a housing 28a having a progressively increasing radial clearance between the outer edges of the blades 27b and the inner surface of the housing 28a, as a result of which, when the impeller is rotated in the direction of the arrow, liquid entering through the aperture 86 and engaged by the blades, is projected vigorously outwardly in a radial direction and forced through a discharge passageway 76 in substantially the manner in which the liquid is discharged effectively by the impeller 27, the construction of the machine not shown in Figs. 6 and 7 being preferably the same as shown and described in connection with Figs. 90 1, 2 and 3.

In addition to the washing and cleaning of fabrics and articles generally as above described, my machine is particularly adapted to the washing of dishes. In using the 95 machine for this purpose, the cylinder 55 and the grid 72 are preferably removed, and a wire basket, for example of the construction shown at 77 in Fig. 4 is employed to contain the dishes to be washed. The basket 77 is provided with upwardly extending ears 78 for engagement with short pins 79 extending inwardly from the end walls of the casing 10 so that when the basket is lowered into the casing, the ears 78 will rest on said pins 105 and hold the bottom of the basket above the bottom of the casing. The basket is preferably of a size leaving a clear space adjacent the curved surface of the side wall 42, as a result of which the washing liquid, for 110 example soap and water moves freely along the surface of the wall 42 and against the deflector 53, by which it is projected downwardly against the dishes to wash them. Where it is desirable to use the machine 115 principally or entirely as a dish washing machine, this result may be somewhat more effectively accomplished by removing the gate 36 by removing the screws 37, and substituting for it the construction shown in Figs. 8 and 9, which consists of a pipe 80 of flat cross section, conformed to rest against the inner curved surface of the side wall 42 and the adjacent bottom surface of the casing, the lower end of the pipe being 120 broadened to extend substantially from end to end of the machine and having an upwardly extending flange 81 at its lower end to receive the screws 37 by which the pipe 125 may be held in position to receive the liquid 130.

discharged by the impeller 27. The pipe 80 is continued until it is adjacent the upper edge of the side wall 42 where it is provided with a pivot rod 82 engaging the adjacent 5 end of a horizontal pipe section 83, the other end of which communicates with a nozzle member 84 having a plurality of discharge openings, for example slits 85 through its lower surface. The pivot rod 82 permits 10 the pipe 83 and nozzle member 84 to be moved out of the path of the basket 77 when it is desired to place the basket in the machine and remove it therefrom, and with the pipe 83 in its operating position, the nozzle 15 member 84 is disposed over the basket so that the streams of liquid emerging from the nozzle member are forcibly projected against the dishes contained in the basket 77. A similar pipe construction may be used with impellers of the type shown in Figs. 6 and 7, if 20 desired.

While I have shown my invention in the particular embodiment above described, it will be understood that I do not limit myself to this exact construction as I may employ equivalents known to the art at the time of the filing of this application without departing from the scope of the appended claims.

30 What I claim is:

1. In a machine of the class described, the combination of a casing having side and bottom walls, a motor comprising a rotor and a field magnet, a shaft extending from said 35 motor, an impeller carried by said shaft, there being passageways for directing liquid in said casing to said impeller and from the latter into the casing in a circulatory path, one of said side walls having a recess constituting said side wall a support for said field magnet, a first cap member detachably connected with said side wall and enclosing said motor and clamping said field magnet on its said support, and a second cap member 45 detachably connected with said side wall and enclosing said impeller.

2. In a machine of the class described, the combination of a casing having side and bottom walls, a motor, a shaft extending from 50 said motor, an impeller carried by said shaft, there being passageways for directing liquid in said casing to said impeller and from the latter into the casing in a circulatory path, one of said side walls having a recess constituting said side wall a part of the housing for said motor, a first cap member detachably connected with said side wall and enclosing said motor and constituting the remainder of said housing, and a second cap 55 member detachably connected with said side wall and enclosing said impeller, said cap members having a common plane of engagement with said recessed side wall extending longitudinally through said shaft, whereby 60 removing said cap members permits the in-

sertion and removal of said shaft and attached parts as a unit.

3. In a machine of the class described, the combination of a casing having side and bottom walls, a motor, a shaft extending from 70 said motor, an impeller carried by said shaft, there being passageways for directing liquid in said casing to said impeller and from the latter into the casing in a circulatory path, one of said side walls having a recess constituting said side wall a part of the housing for said motor, a first cap member detachably connected with said side wall and enclosing said motor and constituting the remainder of said housing, a second cap member 75 detachably connected with said side wall and enclosing said impeller, the side wall opposite to said recessed side wall being curved from said bottom wall upwardly to correspondingly direct liquid delivered by said impeller, a cylinder having a perforate side wall, and bearings mounting said cylinder in said casing adjacent said curved wall and substantially parallel therewith for rotation by liquid flowing on said curved wall, said cylinder having longitudinal ribs along its outer surface extending into said cylinder to tumble the contents thereof during 80 operation of the machine.

4. In a machine of the class described, the combination of a casing having side and bottom walls, a motor, a shaft extending from said motor, an impeller carried by said shaft, there being passageways for directing liquid in said casing to said impeller and from the latter into the casing in a circulatory path, one of said side walls having a recess constituting said side wall a part of the housing for said motor, a first 90 cap member detachably connected with said side wall and enclosing said motor and constituting the remainder of said housing, a second cap member detachably connected with said side wall and enclosing said impeller, the bottom wall of said second cap member being a continuation of the bottom wall of said casing and having a draining aperture therethrough, a plug valve in said draining aperture, a rod extending upwardly from said valve through said second cap member, and a handle on said rod for moving said valve from and into said draining 95 aperture.

5. In a machine of the class described, the combination of a casing having side and bottom walls, a motor, a shaft extending from said motor, an impeller carried by said shaft, there being passageways for directing liquid in said casing to said impeller and from the latter into the casing in a circulatory path, a grid having vertically extending bars and vertically suspended in the path of liquid flow to said impeller, and devices loosely engaging the upper portion of 120 125 130

said grid and permitting its ready insertion and removal as desired.

6. In a machine of the class described, the combination of a casing having side and bottom walls, a motor, a shaft extending from said motor, an impeller carried by said shaft, there being passageways for directing liquid in said casing to said impeller and from the latter into the casing in a circulatory path, one of said side walls having a recess constituting said side wall a part of the housing for said motor, a first cap member detachably connected with said side wall and enclosing said motor and constituting the remainder of said housing, a second cap member detachably connected with said side wall and enclosing said impeller, and a pipe for receiving liquid from said impeller and directing said liquid to the upper part of said casing and there delivering it downwardly in said casing.

7. In a machine of the class described, the combination of a casing having side and bottom walls, a motor, a shaft extending from said motor, an impeller carried by said shaft, there being passageways for directing liquid in said casing to said impeller and from the latter into the casing in a circulatory path, one of said side walls having a recess constituting said side wall a part of the housing for said motor, a first cap member detachably connected with said side wall and enclosing said motor and constituting the remainder of said housing, a second cap member detachably connected with said side wall and enclosing said impeller and a pipe extending from adjacent said impeller to the upper part of said casing to deliver liquid from said impeller downwardly into said casing, said pipe having a hinged joint in its upper portion permitting moving the upper part of the pipe from the upper part of said casing when placing articles in and removing the same from the casing.

45. 8. In a machine of the class described, the combination of a casing for receiving articles to be cleaned, a water impeller, said casing having supply and discharge passages communicating with said impeller, a shaft supporting said impeller and extending therefrom, bearings for said shaft, a first motor element comprising a rotor secured to said shaft, a second motor element surrounding said rotor and co-operating therewith, said casing having a conformation constituting a support for said second motor element and said shaft bearings, and a cap detachably connected with said casing and enclosing said motor elements and clamping said second motor element and said shaft bearings in place, whereby said casing and said cap constitute the frame housing of said motor elements.

65. 9. In a machine of the class described, the combination of a casing for receiving articles

to be cleaned, a water impeller, said casing having supply and discharge passages communicating with said impeller, a shaft supporting said impeller and extending therefrom, bearings for said shaft, a first motor element comprising a rotor secured to said shaft, a second motor element surrounding said rotor and co-operating therewith, said casing having a conformation constituting a support for said second motor element and said shaft bearings, a first cap detachably connected with said casing and enclosing said motor elements and clamping said second motor element and said shaft bearings in place, whereby said casing and said cap constitute the frame housing of said motor elements, said casing having a recess constituting a part of the impeller compartment, and a second cap detachably connected with said casing and constituting the remaining part of the impeller compartment, whereby with said caps removed said shaft and the parts secured thereto may be removed as a unitary structure and attaching said first cap to said casing assembles and holds the motor elements in operative relation.

In witness whereof, I hereunto subscribe my name this 20th day of December, A. D. 1929.

SAMUEL C. SHAFFNER.
